UNITED STATES PATENT OFFICE.

ELLERY C. WRIGHT, OF CAMPELLO, MASSACHUSETTS, ASSIGNOR TO JAMES W. BROOKS, TRUSTEE, OF SAME PLACE.

LAST AND SUPPORT FOR THE SAME.

SPECIFICATION forming part of Letters Patent No. 340,690, dated April 27, 1886.

Application filed June 8, 1885. Serial No. 168,033. (No model.)

To all whom it may concern:

Be it known that I, ELLERY C. WRIGHT, of Campello, county of Plymouth, and State of Massachusetts, have invented an Improvement in Lasts and Supports for the Same, of which the following description, in connection with the accompanying drawings, is a specification, like letters on the drawings representing like parts.

10 In heel-nailing machines the spindle carrying the last-holding pin or pins is made adjustable vertically, in order to enable the bottom of the last to be maintained at the proper level to insure the co-operation therewith of the pressing and nailing mechanism, and when boots or shoes are to have heels automatically nailed thereon while yet upon the last upon which they were lasted, considerable time is lost and difficulty experienced in adjusting the 15 spindle to place the bottom of the last in proper position, such adjustment being necessary owing to variations in the thickness of the cone or heel of the last vertically. The last is provided with one or more vertical holes, 20 to be entered by the last-holding pin or pins.

The object of this invention is to secure the placing of the bottom of the last in the same horizontal position, notwithstanding variations in thickness of the cone or heel part, 25 and to secure the proper position with the same last-pin without change of its position.

In accordance with the invention herein contained the last-pins upon which the last is placed equal in length the thickness of the cone or heel of the thickest last to be employed, and the last is bored through at its cone or heel in the direction of its vertical thickness, and the bottom of the last is provided with a metallic bottom plate or rest, against which 30 the end or ends of the last-pins will strike to support the last before the cone or heel strikes the block attached to the lower end of the spindle and containing the last-holding pins.

The drawing represents in side elevation a 45 last embodying this invention, the spindle, block, and pins being shown in elevation.

The wooden last A, of any desired shape, is bored vertically through the cone or substance of the heel, and at the bottom of the last, by 50 screws 2 or otherwise, is applied a rest-plate,

B, of metal. The spindle C has secured to it the block D, from which extend two pins, e e, of greater length than the thickness vertically of the cone or heel of the thickest last to be used, so that the last will always be supported by the pins e e acting against the interior of the plate B, rather than by the cone of the last resting directly upon the block D, as heretofore.

By determining the position of the last by 60 the plate and pins it is possible to always insure the same level for the bottom of the last, no matter what may be its thickness vertically.

The holes in the last are shown as lined with metal tubes H, which, besides saving wear 65 upon the last, prevent splitting under strain. The tubes might be closed at their inner ends, the pins coming against the closed ends of the tubes, the closed ends thus serving as rest-plates.

The parts C, D, and e e are common to the McKay & Bigelow heelers-machines in common use, except as to the length of the pins e e.

When the usual leather heel is being attached to the sole of the boot or shoe, held on the last A in usual manner, the pressure exerted to drive the nails and to compress the heel solidly is borne by the plate B and the pins resting against it, thus doing away with 80 the liability of splitting the cone or heel of the last, which frequently occurs when the last itself touches the block D or directly receives the pressure, and by the employment of two pins the last is held from being twisted out of 85 the proper straight line.

It will be noticed that the last does not touch the block D, and that the ends of the pins e e, acting against the plate B, take all the pressure, and the wood of the last is not subjected 90 to pressure.

I do not broadly claim the pin and plate B. I claim—

A spindle and attached block having two pins, e e, of greater length than the vertical 95 thickness of the cone or heel of the last, combined with a last having two holes to receive the said pins, and having at or near its bottom a metal rest-plate, against which bear the ends of the said pins to determine the position 100

of the bottom of the last, the said plate and pins sustaining the pressure exerted when the heel is being applied, the last being supported only by the said pins, the latter preventing 5 the tipping or twisting of the bottom of the last out of the proper plane, all substantially as described.

In testimony whereof I have signed my name to this specification in the presence of two subscribing witnesses.

ELLERY C. WRIGHT.
